UNITED STATES PATENT OFFICE.

FRANCIS M. LECHNER, OF COLUMBUS, OHIO.

MOTOR-TRUCK.

SPECIFICATION forming part of Letters Patent No. 451,942, dated May 12, 1891.

Application filed July 23, 1890. Serial No. 359,696. (No model.)

To all whom it may concern:

Be it known that I, FRANCIS M. LECHNER, a citizen of the United States, residing at Columbus, in the county Franklin and State of Ohio, 5 have invented a certain new and useful Improvement in Motor-Trucks, of which the following is a specification.

My invention relates to the improvement of motor-trucks, and has particular relation 10 to that class of trucks or cars employed in supporting and moving electric motors for mining-machines.

The objects of my invention are to provide 15 a motor car or truck with improved means for driving the same forward or backward to regulate the tension of the mining-machine operating rope or belting, to admit of the driving mechanism being so set as to prevent its interference with the free transportation 20 of the car to new locations, to provide said truck or car with an improved reel for taking up or letting out the cables connecting the motor and dynamo without breaking the electrical current, and to accomplish these objects 25 without unusual expense or complication.

In the accompanying drawings, Figure 1 is 30 a plan view of my improved truck, showing a motor thereon. Fig. 2 is a side elevation of the same with the motor removed. Fig. 3 is a side elevation in detail of one end of the 35 reel. Fig. 4 is a section on line $x-x$ of Fig. 5. Fig. 5 is a side view, partly in section, of one of the ground-wheels with the worm-wheel and means for operating it; and Fig. 6 is a 40 detail sectional view on line $y-y$ of Fig. 1.

Similar letters refer to similar parts throughout the several views.

a represents a flat bed or truck-body which 45 is supported upon ground or truck wheels b . c represent the axles or transverse shafts, which, as shown, are supported in suitable bearings c' , depending from the under side of the bed a . Each end of each of these axles has fixed thereon on the outer side of the bed a a worm gear-wheel d , said worm-wheel having formed therewith and projecting from its outer side a short cylindrical neck or arm e , the outer 50 end of which is bolted or otherwise secured to the inner face of the ground-wheel b . The wheels b and d and the connecting-neck e may, however, be formed of one piece of

metal, if desired, the object being to throw the two wheels far enough apart to prevent the worm from touching the ground-wheel when in engagement with the worm-wheel. 55

As shown in the drawings, the axles c extend transversely beneath the bed on opposite sides of the center of the length of the latter.

f represents a horizontal shaft, which is 60 journaled in suitable bearings f' , which project upwardly from the upper side of the bed adjoining one side thereof, and which support said shaft f above the worm gear-wheels, as shown. Carried by the shaft f at such 65 points as to normally engage with the worm-gear d are worm-wheels g . Projecting upwardly from the side of the bed a at a point in rear of the worm-wheel is an intermediate shaft-bearing piece h , through which the shaft 70 f passes loosely. Fixed on said shaft and normally abutting against the rear side of said intermediate bearing-piece is an enlargement or collar k .

i represents a clip or locking-piece, which 75 consists of a short flat plate provided at each end with two downwardly-extending fingers, said locking-clip being adapted to lock the shaft f against horizontal movement by dropping said clip downward until its fingers embrace opposite sides of the shaft f , and the inner sides of said fingers abut against the outer sides of the collar k and the head of the bearing-piece h . The rear end of the shaft 80 f is provided, as shown, with a suitable crank- 85 handle.

m represents a reel base-block, which is supported upon the rear end portion of the truck-bed, and which, as shown, is provided at each end with an upwardly-extending 90 standard m' . The upper end of each of these standards is slotted, as shown, to form a bearing for the spindle of a reel-shaft n . This reel-shaft is provided with end disks n' and a central dividing disk n^2 . 95

n^3 represent flat contact-rings, one of which is secured to the outer side of each of the disks n' about the center thereof. The outer end of each of the spindles n^4 of the shaft n extends through a spindle-hole formed in the 100 center of the length of a horizontal bar or arm n^5 , which is secured to the outer side of the

standard m' . Each of the projecting ends of each of these arms n^5 has secured thereto the upper end of a spring contact-strip o , said contact-strip extending downwardly and 5 thence inwardly and upwardly in an approximately U-shaped form, and having its inner end portion in frictional contact with the surface of the ring n^3 .

One of the outwardly-projecting ends of 10 the shaft-spindle is provided with a crank-handle p .

q represent the cables or electric conductors, which are coiled, as shown, upon the reel-shaft n , on opposite sides of the dividing- 15 disk n^2 , and which lead from said reel to the dynamo or supply-line. These cables are connected with the contact-rings n^3 by having their ends passing through the disks n' , as shown in Fig. 3 of the drawings.

20 S represents a suitable electric motor, which is supported, as shown, upon the central portion of the truck, and with which an electric connection is made from the cables q by means of motor-wires w , which connect with contact-strips o at opposite ends of the reel, as shown.

s' represents the motor-shaft, which, through its pinion s^2 , transmits motion to a gear-wheel s^3 , the latter being carried by a shaft journaled in horizontal bearings s^4 at the forward portion of the machine. This shaft carries on its forward end a beveled gear-wheel t , which transmits motion to a vertical pivoted or journaled shaft t' by gearing with a gear-wheel t^2 thereon. The shaft t' also carries, as shown, the mining-machine drive-wheel t^5 , which has its periphery grooved to receive the driving-rope t^3 .

40 The operation of the improvements herein shown and described is substantially as follows: It being desired to loosen the tension of the driving-rope t^3 by decreasing the distance between the mining-machine and the truck, the latter is moved forward the desired 45 distance by rotating the shaft f through the operation of its handle l . This rotation of the shaft f will, through the meshing of the worm g and the worm-gear d , result in transmitting motion to the latter and to the ground-wheels 50 b , with which said worm-gears are connected, thus causing the desired movement of the truck. It is obvious that the direction in which the truck is moved depends upon the direction in which the shaft f is rotated; but 55 in case the truck is driven forward it will be seen that the tension of the operating or power rope t^3 will be decreased, thus admitting of any desired forward movement of the mining-machine and of the adjustment of the tension of its rope to increase or decrease its binding power on the peripheries of both the truck and mining-machine drive-wheels. In case it is desired to move the truck from one 60 point to another in a mine, the locking-clip i 65 may be withdrawn from its embrace of the bearing-head h and collar k and the shaft f driven by proper rotation a sufficient distance

to the rear to throw the worms g and worm-gears d out of engagement. The truck may then be pushed or otherwise moved upon its ground-wheels to the desired point. 70

During any of the above-described forward movements of the truck the cable q will gradually unwind from its reel-shaft n , and in case of a rearward movement of the truck the slack caused in said cables may be taken up from said reel-shaft by the forward rotation of the latter. As the forward and backward adjustment of the truck is frequently accomplished while the mining-machine is in operation, it is desirable that the circuit between the dynamo and motor be kept closed, and thus obviate the necessity of stopping the machine during this movement or breaking the circuit. This object is attained through the herein-described connection of the cables and contact-rings n^3 , the continuous frictional contact of the contact-strips o , and said contact-rings and the connection of said contact-strips with the motor. 80 85 90

From the construction herein shown and described, it will be seen that the truck may be moved forward or backward, as desired, to increase or decrease the tension of the rope t^3 , and that during these movements 95 the operation of the machine is in no way retarded by the breaking of the current in taking up or letting out the cable-conductors.

Having now fully described my invention, what I claim, and desire to secure by Letters Patent, is—

1. In a motor-truck for mining-machines, the combination, with the truck-body, its axles and ground-wheels, and worm gear-wheels connected with said ground-wheels, 105 of loosely-journalized shaft f , worms g thereon, which normally mesh with worm-gears d , an intermediate shaft-bearing piece h , a fixed collar on said shaft, and a detachable clip i , embracing said collar and an intermediate bearing-head, substantially as described.

2. In a motor-truck, the combination, with the body a , a motor thereon, and a machine drive-wheel driven from said motor, of a reel-shaft n , journaled upon said truck and having wound thereon the conductors q , a dividing-disk n^2 between the conductors, reel-disks n' , disk contact-rings n^3 , with which said conductors' ends are connected, spring-strips o , supported in frictional contact with the rings n^3 , and wires t , connecting the motor and said spring-strips, substantially as described.

3. The combination, with a motor-truck for mining-machines, of a motor and tool-operating mechanism mounted thereon, slotted standards secured to the truck, a horizontal bar on each standard, having a spindle-hole, a shaft in the standards, having a spindle projecting through each of the spindle-holes of the bars, disks on the shaft, the outer ones of which are each provided with a contact-ring, a contact-spring connected with each end of the bar and having its inner end in 125 130

engagement with the ring on the disk at that end of the shaft, a wire for connecting each bar with the motor, electric conductors wound upon the shaft with their ends in contact with the rings on the disks, and means for rotating the shaft to take up or pay out the conductors without breaking the electrical

contact between the motor and the conductors, substantially as described.

FRANCIS M. LECHNER.

In presence of—

W. E. MOLING,

FRANK N. SLADE.
